CLAIM

The ornamental design for a type font, as shown and described.

DESCRIPTION

FIG. 1 is a face view of a type font showing my new design;

FIG. 2 is a face view of a modified embodiment thereof;

FIG. 3 is a face view of a second modified embodiment thereof;

FIG. 4 is a face view of a third modified embodiment thereof; and,

FIG. 5 is a face view of a fourth modified embodiment thereof.
